UNITED STATES PATENT OFFICE.

MAXIMILIAN CHARLES SCHWEINERT, OF WEST HOBOKEN, NEW JERSEY.

STOPPER FOR WATER-BOTTLES OR THE LIKE.

1,383,767.

Specification of Letters Patent.

Patented July 5, 1921.

Application filed November 12, 1915. Serial No. 61,037.

To all whom it may concern:

Be it known that I, MAXIMILIAN CHARLES SCHWEINERT, a citizen of the United States of America, residing in West Hoboken, in the county of Hudson and State of New Jersey, have invented certain new and useful Improvements in Stoppers for Water-Bottles or the like, of which the following is a specification.

10 This invention relates to stoppers for water bottles or the like, and aims to provide certain improvements therein.

The invention is particularly directed to that type of water bottle stopper in which an enlarged neck member is provided, usually of oval form, which is fastened within the neck of the water bottle. The invention provides in this type of stopper a construction in which the stopper proper is always 20 maintained in its screw-threaded socket piece, means being provided whereby when the stopper is unscrewed to a certain extent the passages through the structure are open, and when it is screwed down such passages 25 are closed. The invention includes certain other features of construction which will be hereinafter more fully described.

According to the drawings which illustrate several forms of the invention,—

30 Figure 1 is a central vertical section of the neck, the stopper being shown in elevation.

Fig. 2 is a similar section at right angles to that of Fig. 1.

35 Fig. 3 is a similar section to Fig. 1, showing a slightly modified construction.

Fig. 4 is a plan of Fig. 3.

Referring to the drawings, let A indicate the neck member which is shown of oval 40 form, as best seen in Fig. 4. In the construction illustrated the neck member is formed of a single piece of sheet metal having a bottom wall *a* and side wall *b* which are usually concave to provide a better connection with the rubber neck of the water 45 bottle. The neck member A is preferably formed with a centrally disposed opening *c* around the margin of which is fixed the socket member B. The parts may be joined 50 in any convenient manner, preferably by forming an internal flange *d* on the socket member over which is turned a flange *e*

formed on the neck member. The socket B is preferably constructed of sheet metal formed with internal and external threads, 55 the former of which is designed to receive the stopper C.

According to the present invention I provide a construction in which the stopper is retained in place in the socket member 60 during all conditions of use. To this end I form an aperture or series of apertures *f* in the socket member immediately above the flange *e*, such apertures leading to the space 65 *g* formed by the neck member A. When the stopper is screwed to its upper position, as indicated in Fig. 1, the apertures or ports *f* are open and permit water to flow into and out of the bottle for filling and discharging purposes. When the stopper is screwed to 70 its lower position, its packing *h* is pressed against the flange *e* (or other seat) and entirely closes access through the apertures *f*.

In the preferred construction as thus described the neck member A constitutes a receptacle into which the water is poured, thus increasing the effective capacity of the funnel D of the water bottle, and forming a filling chamber into which the water is poured in filling the bottle. I hence prefer 80 that the neck member A be arranged within the water bottle neck with its open end uppermost, since its additional capacity when so arranged enlarges the effective capacity of the water bottle funnel.

85 In the construction shown it is not necessary to remove the stopper from the socket member B; all that is requisite is that the stopper be unscrewed to a sufficient extent to uncover the apertures or ports *f*. I prefer, however, to provide some means by which the stopper is limited in its upward motion so that by carelessness or otherwise it will not be wholly unscrewed and removed from the bottle. One construction for accomplishing this result is indicated in Fig. 1, wherein I provide a screw-threaded collar *j* having a flange *k* which fits over a complementary flange *l* formed on the water bottle stopper. When the collar is screwed 95 down over the exterior of the socket member it constitutes an effective stop which prevents the complete removal of the stopper. In order to simplify the assembly of the 100

parts, I prefer to construct the collar *j* with a recess or recesses *m m* (Fig. 4) in its flange *k*, so that the collar may be easily slipped over the handle *n* of the stopper.

5 If desired, however, the socket member may be permanently connected to the stopper by means, such as shown in Fig. 3, wherein the screw-threaded collar *j* is omitted and a flange *o* is formed at the top of the socket member *B'*.

10 While I have shown and described several forms of the invention, it will be understood that I do not wish to be limited thereto, since various changes may be made 15 therein without departing from the spirit of the invention.

What I claim is:—

1. In a device of the character described, an enlarged neck member adapted to be secured 20 within the neck of a water-bottle or the like having fixed thereto a reduced socket member, a stopper screwing in said socket member, a seat at the lower part of said socket member, and apertures above said seat, 25 said apertures constituting passages to the water bottle when the stopper is in its upper position.

2. In a device of the character described, an enlarged neck member adapted to be secured 30 within the neck of a water-bottle or the like having fixed thereto a reduced socket member, a stopper screwing in said socket member, a seat at the lower part of said socket member, apertures above said seat, 35 said apertures constituting passages to the water bottle when the stopper is in its upper position, and means for retaining said stopper in said socket member to normally prevent separation of said parts.

40 3. A device of the character described comprising an enlarged neck member adapted to be secured within the neck of a water bottle or the like, a reduced socket member fixed to the lower wall of said neck member, a seat at the point of juncture of said parts, 45 a stopper screwing into said socket member, and apertures above said seat adapted to form passages for the water when the stopper is in its uppermost position.

50 4. A device of the character described comprising an enlarged cupped neck member adapted to be secured within the neck of a water bottle or the like having a lower wall and an open top, a reduced socket member 55 fixed to the lower wall of said neck member and at least partially contained within said neck member, a seat at the point of juncture between said parts, a stopper adapted to screw in said socket member, and said socket member formed with apertures above said seat and within the cup of said neck member adapted to form passages when said stopper is in its upper position.

5. In a device of the character described, 65 a neck member adapted to be secured within

the neck of a water bottle or the like, said neck member comprising a plate adapted to extend across the neck of the water bottle and sides which make contact with the neck of the water bottle, and a socket member 70 upstanding from said plate and adapted to receive a stopper, said socket member having a filling opening therein near the surface of said plate.

6. In a device of the character described, 75 a neck member adapted to be secured within the neck of a water bottle or the like, said neck member comprising a plate adapted to extend across the neck of the water bottle and sides which make contact with the neck 80 of the water bottle, a socket member upstanding from said plate and adapted to receive a stopper, said socket member having a filling opening therein near the surface of said plate, and a seat immediately below said 85 filling opening.

7. In a device of the character described, a neck member adapted to be secured within the neck of a water bottle or the like, said neck member comprising a plate adapted to 90 extend across the neck of the water bottle and sides which make contact with the neck of the water bottle, and a socket member upstanding from said plate and adapted to receive a stopper, said socket member having 95 a filling opening therein near the surface of said plate, said socket member being substantially the height of the stopper plus the height of said filling opening.

8. In a device of the character described, 100 a neck member adapted to be secured within the neck of a water bottle or the like, said neck member comprising a plate adapted to extend across the neck of the water bottle and sides which make contact with the neck 105 of the water bottle, and a socket member upstanding from said plate and adapted to receive a stopper, said socket member having a filling opening therein near the surface of said plate, said plate and sides being in 110 the form of a cupped sheet of metal.

9. In a device of the character described, a neck member adapted to be secured within the neck of a water bottle or the like, said neck member comprising a plate adapted to 115 extend across the neck of the water bottle and sides which make contact with the neck of the water bottle, a socket member upstanding from said plate and adapted to receive a stopper, said socket member having a filling 120 opening therein near the surface of said plate, and said socket member and sides both projecting from the same side of said plate.

10. In a device of the character described, a neck member adapted to be secured within the neck of a water bottle or the like, said neck member comprising a plate adapted to 125 extend across the neck of the water bottle and sides which make contact with the neck of the water bottle, and a socket member up- 130

standing from said plate and adapted to receive a stopper, said socket member having a filling opening therein near the surface of said plate, said plate and sides being in the 5 form of a cupped sheet of metal, and said socket member and sides both projecting from the same side of said plate.

In witness whereof, I have hereunto signed my name in the presence of two subscribing witnesses.

MAXIMILIAN CHARLES SCHWEINERT.
